[57] CLAIM

The ornamental design for a physical exerciser, as shown and described.

DESCRIPTION

FIG. 1 is a top, front and right side perspective view of a physical exerciser showing my new design;
FIG. 2 is a right side elevational view thereof;
FIG. 3 is a left side elevational view thereof;
FIG. 4 is a top plan view thereof;
FIG. 5 is a front elevational view thereof;
FIG. 6 is a top, front and right side perspective view of a modified embodiment of the design shown in FIGS. 1-5;
FIG. 7 is a right side elevational view thereof;
FIG. 8 is a left side elevational view thereof;
FIG. 9 is a top plan view thereof; and
FIG. 10 is a front elevational view thereof.
